UNITED STATES PATENT OFFICE.

FERDINAND STRAUSS, OF NEW YORK, N. Y.

MECHANICAL TOY.

Application filed October 22, 1924. Serial No. 745,138.

To all whom it may concern:

Be it known that I, FERDINAND STRAUSS, a citizen of the United States of America, residing at New York city, county of New York, and State of New York, have invented certain new and useful Improvements in Mechanical Toys, of which the following is a specification.

This invention relates to mechanical toys 10 and in particular to a type embodying movable figures or characters.

An object of the invention is to provide 15 a toy in which a concealed figure or character makes its appearance periodically and automatically during the travel of the toy.

A further object is to provide a toy in 20 which the forward character between the shafts shall have a life-like movement, and shall be operated from the concealed figure operating mechanism which may be a part 25 of the vehicle propelling means.

A still further object is to provide a vehicle toy having a novel shaped body such as an egg, from which a chicken emerges at 30 intervals, it being understood that the vehicle body may be shaped as desired and the figure used therewith to be suitable such, for instance, as a jack-in-the-box.

A still further object is to provide a propelling mechanism which will operate the 35 cover in the body of the vehicle, the character in the body and the forward character all in unison or proper sequence as desired.

In the drawing wherein I have shown a 40 preferred embodiment of my invention;

Figure 1 is a top plan view partly in section, of my improved toy showing the interior operating mechanism in the vehicle body,

Figure 2 is a view in side elevation, the 45 body of the vehicle being shown in section taken on line 2—2 of Fig. 1 to illustrate the propelling mechanism,

Figure 3 is a rear elevation in section of the vehicle body showing the arrangement 50 of the mechanism, and

Figure 4 is a top plan view of the toy on a reduced scale showing the lid or trap-door arrangement in the top of the vehicle body.

In referring to the drawing, it is to be understood that the showing of an egg-shaped vehicle body with a chicken therein is for the purpose of illustrating only one 55 of the ways in which my invention may be applied, it being evident that any suitable

vehicle body and figure might be used in the same manner, without departing from the spirit of my invention.

In the drawing 5 indicates a vehicle body 60 of egg-shape, which for the purpose of manufacture may be made in two halves, an upper half 6 and lower half 7, suitably joined as at 8. The lower half of the body is provided with an axle 9 which extends 65 beyond the sides thereof and carries the ground engaging wheels 10 which propel the vehicle, through the medium of a suitable driving mechanism which consists of a driven disc 11 secured to axle 9 and having 70 integrally formed thereon a pinion 12 which is engaged by an intermediate gear 13 of similar shape, the pinion 14 thereof meshing with, and being driven by, the driving gear 15 which is mounted on one end of the 75 spring drum shaft 16. The gear 15 is of course engaged by one end of a coiled spiral spring 17 wound about a drum 18, the end of the drum opposite the gear 15 carrying a ratchet 19 which is also secured to the 80 drum shaft 16, the latter being extended beyond the body of the vehicle to form a winding key 20.

With the exception of the axle 9, the 85 shafts are all journaled in side frames 21 and 22, which are soldered or otherwise secured in the lower half 7 of the vehicle body. On the side frame 22 there is pivoted a suitable ratchet engaging pawl 23 adjacent the ratchet 19 so that the spring may 90 be wound, in the usual manner.

The end of the spring 17 is attached to the ratchet. The side plate 22 carries a bracket 24, the end of which is curved to provide a bearing as at 25 for the intermediate gear shaft 26, the bracket being provided with suitable opposed openings 27 through which is adapted to loosely pass the shank 28 of the chicken figure 29. This figure is supported on a swinging arm 30 100 which is pivotally attached to the bar 31 held in, and extending between, the side plates 21 and 22, the arm 30 being provided with an elongated slot 32 in its rear portion through which passes the shank 28 of the figure 29 before referred to. This slot allows for a swinging movement of the arm, while the openings 27 in the bracket act as a guide to maintain the chicken figure 29 in upright position and allow for a vertical movement thereof. The chicken figure 29 105 may be slightly offset from the shank to

position it in the center line of the vehicle body.

The axle 9 is offset at the center of the vehicle body as at 33 and in this portion 5 is engaged by one end of a character rocking arm 34, the forward end of which pivotally engages a projection 35 in the bottom of the animal figure 36, in this instance a rabbit, so that when the axle 9 revolves it 10 will rock the figure 36 on its pivot point formed by the engagement of the supporting shafts 37 with the sides of the figure 36. It will be particularly noted that the pivot point of the shafts and figure is in line with 15 the pivot point of the rock arm 34 and the figure, and both are at the balancing center of the figure, so that, in motion, the rock arm 34 will impart a quick jumpy-like movement to the figure.

20 The driving gear 15 is provided on its inner face with a plurality of spaced cam pieces 38 which successively engage during the revolution of said gear, an extended portion 39 formed on the swinging arm 30. 25 The arm is so shaped that it will rest on the bracket 24 when its extended portion 39 is not in contact with one of the cam pieces 38, in which position the chicken figure 29 will be in its lowermost position, it being 30 understood that the figure moves downward independently of the arm due to gravity. When the arm is raised by a cam piece 38 it raises the chicken-figure through a suitable opening 40 in the top of the upper 35 half 6 of the vehicle body, the opening 40 being closed by a trap-door or lid 41 which conforms to the shape of the vehicle body and is hinged thereto as at 42. This lid carries a projecting piece 43 which extends 40 into the interior of the vehicle body and in position to be engaged by another offset portion 44 in the arm 30, so that when the arm is raised, the end thereof will raise the lid faster than the chicken figure is projected upwardly through the opening 40 in the vehicle body, so that the lid will open 45 first and then the figure will appear, and when the cam piece 38 passes from under the offset 39 of the arm 30 the figure will disappear and the lid will close simultaneously.

50 It will be noted that the cam pieces 38 are wave-like so that in riding under the offset 39 they will impart a jump movement 55 to arm 30 which will cause a like movement of the chicken figure while it is in position in the opening 40 in the vehicle body.

The vehicle body is provided with a pilot wheel 45 at its forward end and while illustrated as fixed the same way be pivoted to cause the vehicle to travel in circles or in any desired direction.

It will be seen therefor that I have provided a novel toy embodying a fanciful com-

bination of figures which operate in a novel 65 manner to amuse children, while at the same time I provide a toy in the nature of a vehicle which will be self propelled.

Having described my invention, what I claim is:—

1. A toy comprising a vehicle member of substantially egg shape, a propelling mechanism therefor, a chicken figure in said vehicle member, a figure mounted forwardly of said member, means operated by said propelling mechanism for imparting a vertical movement to the first mentioned figure and a rocking movement to said second mentioned figure.

2. A toy vehicle comprising a body member having an opening therein, a cover for said opening, a figure in said body member, a character pivotally carried by the body member forwardly thereof, a propelling mechanism for said vehicle, a pivoted arm in said body member adapted to be operated upon by said propelling mechanism, means on said arm for periodically opening said cover and moving said figure through the opening in the body member simultaneously, and means associated with said propelling mechanism for rocking said pivoted character during the operation of said toy.

3. A toy vehicle comprising a hollow body having an opening therein, a cover for said opening, a lever in said body and adapted to have pivotal movement, a figure separably associated with said lever and adapted to be raised thereby through said opening, and means on said cover for engaging said lever whereby the latter will be opened at the time the figure is raised through the opening.

4. A toy vehicle comprising a hollow body having an opening therein, propelling mechanism comprising a gear wheel in said body, a lever in said body, an offset portion on said lever, projections on said gear wheel adapted to engage the offset portion of said lever when the mechanism is operating whereby the lever is raised periodically, and a figure on said lever so arranged as to pass through the opening in the body of the vehicle when the lever is raised.

5. A toy vehicle comprising a hollow body, a hinged door in said body, a toy propelling mechanism comprising a gear wheel, a lever, projections on said gear wheel for periodically raising one end of said lever, a figure carried by said lever, and adapted to pass through the door opening and means on said lever for opening the door so that the figure can subsequently pass through the door opening.

In testimony whereof I hereunto affix my signature.

FERDINAND STRAUSS.
